United States Patent Office

Des. 179,705
Patented Feb. 12, 1957

179,705

PITCHER

Louis M. Schnitzer, Brooklyn, N. Y., assignor to Everlast
Metal Products Corp., a corporation of New York

Application August 30, 1955, Serial No. 37,718

Term of patent 14 years

(Cl. D44—21)

The single figure is a perspective view of a pitcher, showing my new design.

The opposite side of the pitcher appears substantially the same as the side depicted in the drawing.

I claim:

The ornamental design for a pitcher, as shown and described.
